US0D1000515S

(12) **United States Design Patent** (10) **Patent No.:** **US D1,000,515 S**
(45) **Date of Patent:** **** Oct. 3, 2023**

(54) **PAYMENT CARD**

(71) Applicant: **Block, Inc.**, San Francisco, CA (US)

(72) Inventors: **Ayokunle Omojola**, San Francisco, CA (US); **Robert Andersen**, San Francisco, CA (US); **Vadim Litvak**, San Francisco, CA (US)

(73) Assignee: **Block, Inc.**, Oakland, CA (US)

(**) Term: **15 Years**

(21) Appl. No.: **29/831,680**

(22) Filed: **Mar. 22, 2022**

Related U.S. Application Data

(63) Continuation of application No. 29/586,095, filed on Nov. 30, 2016, now Pat. No. Des. 954,145.

(57) **CLAIM**

The ornamental design for a payment card, as shown and described.

DESCRIPTION

FIG. 1 is a front view of a first embodiment of a payment card showing my new design.

FIG. 2 is a rear perspective view thereof.

FIG. 3 is a rear view thereof.

FIG. 4 is a top view thereof.

FIG. 5 is a bottom view thereof.

FIG. 6 is a left side view thereof.

FIG. 7 is a right side view thereof.

FIG. 8 is a front view of a second embodiment of the payment card.

FIG. 9 is a rear perspective view thereof.

FIG. 10 is a rear view thereof.

FIG. 11 is a top view thereof.

FIG. 12 is a bottom view thereof.

FIG. 13 is a left side view thereof; and,

FIG. 14 is a right side view thereof.

The broken-line showing of features on the payment card illustrate unclaimed environment and form no part of the claimed design. The broken-line text illustrates unclaimed environment and forms no part of the claimed design.

1 Claim, 10 Drawing Sheets
